UNITED STATES PATENT OFFICE

103,988

DESIGN FOR A COMFORTABLE

Joseph Goodstein, New York, N. Y.

Application March 6, 1937, Serial No. 68,042

Term of patent 3½ years

To all whom it may concern:

Be it known that I, Joseph Goodstein, a citizen of the United States of America, residing in Manhattan, county and State of New York, have invented a new, original, and ornamental Design for a Comfortable, of which the following is a specification, reference being had to the accompanying drawing, forming part thereof, wherein:

The figure is a plan view of a comfortable showing my new design.

The rear portion of the comfortable is identical in appearance to the design disclosed on the drawing.

I claim:

The ornamental design for a comfortable, substantially as shown, and described.

JOSEPH GOODSTEIN.
